BELT RACK

Ida Weinman, 67—74 Saunders St.,
Rego Park, N.Y. 11374

Filed Apr. 11, 1968, Ser. No. 11,415

Term of patent 14 years

Int. Cl. D6—99

U.S. Cl. D33—3

FIG. 1

FIG. 2

FIG. 3

FIG. 4

FIG. 5

FIG. 1 is a front elevational view of a belt rack showing my new design;

FIG. 2 is an elevational view looking from the right of FIG. 1, the opposite side being substantially a mirror image of the side shown;

FIG. 3 is a top plan view;

FIG. 4 is a rear elevational view; and

FIG. 5 is a bottom plan view thereof.

I claim:

The ornamental design for a belt rack, as shown and described.
